(57) **CLAIM**

The ornamental design for a shelf label holder as shown and described.

DESCRIPTION

FIG. 1 is a top, left, rear perspective view of a shelf label holder showing our new design;

FIG. 2 is a rear view of the invention illustrated in FIG. 1;
FIG. 3 is a front view of the invention illustrated in FIG. 1;
FIG. 4 is a right side view of the invention illustrated in FIG. 1;

FIG. 5 is a left side view of the invention illustrated in FIG. 1;

FIG. 6 is a top view of the invention illustrated in FIG. 1;
and,

FIG. 7 is a bottom view of the invention illustrated in FIG. 1.

The shelf label holder is shown with a symbolic break line in its length. The appearance of any portion of the article between the break lines forms no part of the claimed design. The parallel diagonal shading lines in the drawings of the shelf label holder indicate transparency.
